UNITED STATES PATENT OFFICE.

GEORGE W. SWIFT, JR., OF BORDENTOWN, NEW JERSEY

CORRUGATING-MACHINE.

1,263,000.

Specification of Letters Patent. Patented Apr. 16, 1918.

Application filed May 2, 1917. Serial No. 165,910.

To all whom it may concern:

Be it known that I, GEORGE W. SWIFT, Jr., a citizen of the United States, residing at Bordentown, in the county of Burlington 5 and State of New Jersey, have invented certain new and useful Improvements in Corrugating-Machines, of which the following is a specification.

The object of this invention is to provide 10 an improved machine for making corrugated paper board, and particularly that class in which but one facing sheet is employed.

Another object is to provide in such a machine an improved mounting for members 15 operative to strip the corrugated sheet from one of the corrugating rolls to which it has a tendency to cling, said mounting being automatically adjustable to accord with changes in the length of said roll due to expansion and contraction.

Still another object is to provide an improved steam manifold with automatic take-up means operative to maintain steam-tight joints with the corrugating rolls as they expand and contract with changes in temperature.

A further object is to provide means for supporting the corrugating rolls of the machine intermediate their ends to prevent 30 their warping under the strains coincident with pressing paper between them, and without hindrance to the passage of webs of said paper therethrough.

And a further object is to provide an improved mechanism for maintaining the glue roll of the machine revolving in both extreme operative and inoperative positions together with means to shift the said roll from one of said positions into the other.

Additional objects and details of the construction of a machine comprising the preferred embodiment of this invention are fully described in the following specification, when read in conjunction with the accompanying drawings in which latter Figure 1 is a side elevation of the machine, with the steam manifold removed; Fig. 2 is a front elevation of the greater position of said machine; Fig. 3 is a vertical section on the line 45

3—3 of Fig. 2; Fig. 4 is a section on the line 4—4 of Fig. 2; Fig. 5 is a section on the line 5—5 of Fig. 2; Fig. 6 is a section on the line 6—6 of Fig. 2; Fig. 7 is a detail section of one of the socketed caps for the rolls; Fig. 50

8 is a detail view of one of the fittings designed to coöperate with said caps; Fig. 9

is a detail view of a spring-adjusting collar for said steam fittings; Fig. 10 is a fragmentary elevation showing the correlation between the corrugating rolls and stripping members; Fig. 11 is an end view of one of said members and its floating mounting; Fig. 12 is a side view of the same; Fig. 13 is a side view of one of the glue-roll stripping members; Fig. 14 is a side elevation of the glue roll mounting; Fig. 15 is a section on the line 15—15 of Fig. 14; and Fig. 16 is a vertical section of the glue tank.

Referring to Figs. 1 and 2 of the drawings the preferred form in which the invention is embodied comprises a pair of upright side frames 1 and 2 provided at their uppermost portions with adjustable bearings 3, upon and between which is revolvably mounted a shaft 4, carrying a roll 5 of paper, 70 from which a continuous web 6 passes downwardly over rollers 7 adjustably mounted by means of brackets 8 upon said frames.

In each of the said side frames is provided a pair of guides 9 between which are 80 slidably mounted three journal boxes 10 in the two upper of which are rotatably mounted the tubular shafts 11 carrying corrugating rolls 12 and 13, while the shaft 14 mounted within the lowermost of said boxes carries a smooth roll 15. Of the corrugating rolls the upper is circumferentially grooved at spaced intervals 16 for the purpose hereinafter described, while the characteristic longitudinal grooves of the lower one are 85 continuous throughout the entire length thereof.

Referring to Figs. 3 and 4, as well as to those above mentioned, each of the central journal boxes is secured by a bolt 17 to said 95 guides at a given elevation, while between the upper and lowermost pairs of said boxes extend trusses 18, carrying brackets 19, which in turn revolvably support rollers 20 and 21, the former being corrugated and 100 two in number while the latter are of the same number but smooth, said rollers evenly coöperating with the adjacent surfaces of the corrugating and smooth rolls, respectively, and operating to prevent said rolls 105 from warping under the strains due to corrugating and compressing the web passing therebetween.

The end portions of the said trusses 18 are secured by means of bolts 24 to the respective upper and lowermost pairs of the journal boxes 10, while the vertical adjustment

of each of the trusses is attained by means of bolts 25 passing through and in threaded engagement with plates 26 in turn secured to adjacent portions 27 of the respective frames 5 1 and 2, said portions being provided with enlarged apertures in alignment with and through which said bolts slidably pass. Every adjustment vertically of said trusses likewise adjusts positions of the idlers 20 10 and 21 after they have been set as above described and with the effect of maintaining a constant and even pressure upon the central portions of the adjacent corrugated and smooth rolls respectively. Said idlers when 15 desired may also be adjusted with respect to the adjacent trusses by means of threaded pins 28 and lock nuts 29, after the adjustment of which the respective plates 19 are secured in fixed position by bolts 30.

20 Each of the corrugated and smooth rolls is hollow throughout its full extent while secured in threaded engagement upon and substantially inclosing the ends thereof are caps 35 (Fig. 7), each being provided centrally with an aperture 36 terminating inwardly in an enlarged concave bearing surface 37, with which latter slidably cooperates the enlarged convex head 38, of a tube 39 (Fig. 8), to the opposite end of which is 30 secured an elbow 40. Slidably mounted upon said tube is a sleeve 41 (Fig. 9), adapted to be secured in a given position by means of a bolt 42 and provided in its opposite faces with spiral bearing surfaces 43, against 35 either of which may press a coil spring 44, which at its opposite end cooperates with the recessed washer 45, in turn slidably engaging the outermost surface of the cap 35 adjacent to the tube 39.

40 Extending from each of the elbows 40 is a tube 48 which at its opposite end is secured in threaded relation with plate 49, in turn bolted to one vertical side 50 of a hollow steam trap 51 and in alignment with an enlarged opening 52, leading through. Said trap is provided with a vertically extending wall or partition 53, which separates from the main portion thereof an elongated, relatively slender drainage compartment 54, 45 from the lowermost end of which leads a drain pipe 55, while into the apertures 56 through said partition are secured relatively small tubes 57 in alignment with the apertures 52 and extending therethrough and 50 thence through each of the respective pipes 48, and connected by elbows 58 (within the elbow 40) with tubes 59, leading through the respective tubes 39 and caps 35 into the large rolls and to the farther end thereof, whence 55 the former are bent downwardly to points closely adjacent to the lower inner surfaces of the said rolls.

With this construction live steam is led into the trap 51 by means of a pipe 60, 65 whence it passes by means of the tubes 48

and 39 into each of the said rolls, where it eventually condenses and in the form of water is forced by the entrance of fresh steam outwardly thereof through the tubes 59 and 57 into the compartment 54 of said trap and to the drain 55. As it is obviously true that the friction between the curved co-operating surfaces of the members 38 and 35 tends to wear the same, any desired quantity of lubricating oil may be injected into said live steam by means of an oil cup 62, leading into the trap 51; said oil being carried by the steam into the respective rolls where a considerable portion of the former is deposited within the groove 63 of the cap 35 or in other ways is made available for lubricating the surfaces previously referred to.

As the web 6, of paper from the roll 5, passes between the frames 1 and 2, it comes into contact with the upper apertured surface of a pipe 64, into which steam is led by means of small pipe 65, which latter is also apertured to permit the escape of steam therefrom. In this manner the said web is moistened by means of steam being directed against it, when the latter condenses and operates to lessen the stiffness of the former, said web then passing through an elongated aperture 66, in an angular guide 67, which is in turn secured at its ends by bolt 68 to adjacent portions of said frames. The web then continues its course passing between the corrugated rolls where the ridges of one press it into the oppositely positioned grooves of the other, said web being separated from, or prevented from adhering to, the surface of the uppermost roll by means of stripping members 70, and is forced to cling to the alternating ridges and grooves of the middle roll until it comes into contact with the smooth surface 71 of a glue roll 72. The corrugated web thence continues around the said middle roll, being prevented from adhering to the roll 72, by means of strippers 73, until there is pressed against the outer glued ridges of said web a facing sheet 74, by means of the smooth roll 15.

Referring to Figs. 10, 11 and 12, there is provided a fixed rod 78, upon which are secured at spaced intervals sleeves 79 by means of set screws 80, said sleeves also being provided with recesses 81, extending inwardly from one face thereof. Surrounding and slidably mounted upon said rod are sleeves 82, provided with pins 83, slidably positioned within the aperture 81, and herein lies one of the principal advantages of this construction. Each of said last-named sleeves is provided integrally with a shoulder 84, to which is secured one of the double pointed concave strippers 70, one end of each of which slides within one of the grooves 16 of the roll 12, and by virtue of its being mounted movably upon the rod 78, it can

readily assume any position longitudinally thereof upon the expansion or contraction of said roll with the injection of steam thereinto, or removal therefrom. Each of the 5 strippers 73, on the other hand is fixedly secured by suitable means to one wall 85, of a glue reservoir 86, and has one of its ends 73' so positioned as to slidably enter one of the circumferential grooves 87 within the outer 10 surface of the glue roll 72.

The arrangement employed for gluing the outer ridges of the corrugated paper comprises the roll 72, hereinbefore described, secured upon a shaft 90 revolubly mounted in 15 bearings 91, and carrying a gear wheel 92, said bearings being secured in any suitable manner to a frame 93, in turn mounted to reciprocate upon a T-shaped track 94, comprising an extension from the frames 1 and 20 2, the adjacent surface of said frame and track being separated by means of anti-frictional roller chain 95, of any suitable construction. When the glue roll is in operation the same is revolved by means of the 25 gear 92 meshing with the gear 95', carried by the roll 13, which in turn is driven by the gear 96 from any suitable source of energy (not shown), and drives the smooth roll 15 by coöperation with the gear 97 30 thereon. When on the other hand operation of the function of the glue roll is not desired, the frame 93 carrying the same is moved to the rear of the track 94 by means of any suitable form of lever and link 98 35 and 98', respectively, where in said rearmost position said roll is revolved by its respective gear meshing with a pinion 99, in turn driven by pinion 100, secured to the same shaft with a sprocket wheel 101, connected 40 by sprocket chain 102, or other suitable means of power transmission, to a gear or pulley 103, which latter is secured to a shaft 104, actuated by a gear 105, meshing with the gear 96. The glue reservoir 86 is provided 45 with a drain outlet 107, and the frame 93 which carries the glue roll has mounted thereon a bracket 108 upon which is mounted a suitable means 109 for wiping all but the desired amount of glue from said roll.

50 The construction of the machine thus described shows a greatly increased efficiency over those formerly employed of a corresponding size, and in addition thereto presents certain novel features which it is desired 55 to protect individually and collectively, among other things there being the automatically adjustable stripping members adapted to take up positions with respect to the corrugating roll immediately upon any 60 change in the temperature thereof; the new construction of the steam manifold for automatic adjustment with changes in temperature of the several rolls; the provision for moistening the paper web as it passes into 65 the machine; the improved mounting for the

glue roll; the means for preventing a bending of the longitudinal axes of the several rolls as paper is corrugated therebetween; and other improvements over the art as hereinbefore described and as hereinafter 70 claimed.

Having thus described my invention, what I claim and desire to protect by Letters Patent of the United States is:—

1. A corrugating machine, comprising a 75 fluted roll, a truss, and an idler carried by said truss and bearing upon said roll, to maintain a rectilinear position of the longitudinal axis of said roll.

2. A corrugating machine, comprising a 80 fluted roll, a truss, and a plurality of adjustable idlers carried by said truss and bearing upon said roll, to prevent a bending of the longitudinal axis of said roll.

3. A corrugating machine, comprising a 85 series of rolls having their axes in a common plane, a truss extending adjacent to the outer rolls of said series, and idlers carried by said trusses and bearing upon said adjacent rolls, to prevent a bending of the longitudinal axes 90 of said outer rolls.

4. A corrugating machine, comprising a roll provided with a circumferential groove, means to heat said roll, a stripping member extending into said groove to separate a 95 sheet from said roll, and a mounting for said member operative to automatically adjust the same longitudinally of and in accordance with a change of temperature in said roll.

5. A corrugating machine, comprising a 100 roll provided with a plurality of circumferential grooves, means to heat said roll, stripping members extending into said grooves to separate a sheet from said roll, and a mounting for each of said members operative 105 to automatically adjust the same longitudinally of and in accordance with a change of temperature in said roll.

6. A corrugating machine, comprising a roll, a stripping member extending into a 110 groove in said roll, and freely movable longitudinally of a member parallel with said roll, and means to prevent said stripping member from moving transversely of said last named member.

7. A corrugating machine, comprising a roll, means to heat the same, stripping members extending into grooves in said roll, and freely movable longitudinally of a member parallel with said roll, and means to prevent 120 said stripping member from moving transversely of said last named member, while they are automatically adjusted by coöperation with the sides of said grooves to correspond with changes in the temperature of 125 said roll.

8. The combination of a stripping member with a mounting therefor, said member being movable upon said mounting in a pre-determined path, and means to restrain said 130

member against movement in any other paths.

9. The combination of a stripping member, with a mounting therefor, said member being adapted to move freely upon said mounting.

10. The combination of a stripping member, with a mounting therefor, said mem-

ber being adapted to move freely in a predetermined path upon said mounting.

In testimony whereof I have affixed my signature in presence of two witnesses.

GEORGE W. SWIFT, JR.
